ATTORNEY

UNITED STATES PATENT OFFICE.

MYRON W. WIARD, OF SAN DIEGO, CALIFORNIA, ASSIGNOR OF ONE-HALF TO C. O. NICHOLS, OF BOSTONIA, CALIFORNIA.

SEPARABLE KEY.

1,074,075.

Specification of Letters Patent. Patented Sept. 23, 1913.

Application filed May 5, 1913. Serial No. 765,434.

To all whom it may concern:

Be it known that I, MYRON W. WIARD, a citizen of the United States, and resident of San Diego, county of San Diego, and State of California, have invented certain new and useful Improvements in Separable Keys, of which the following is a specification.

My invention relates to a door key made in parts, one of which remains in the lock while the door is locked and the other part is removed from the lock and may be carried in the pocket of the user, if desired.

The objects of my invention are, first, to provide a key which may be used on either side of the door for locking the same, and a portion left in the lock so that a pass or other key cannot be inserted in said lock; second, to provide such a key in which the portion left in the door is not readily turned from either side for unlocking the door; third, to provide such a device that is simple, economical of construction, durable and easily operated, and fourth, to provide keys with a plurality of different shaped connecting parts so as to increase the variety of keys.

With these and other objects in view as will appear hereinafter, my invention consists of certain novel features of construction, combination and arrangement of parts as will be hereinafter described in detail and particularly set forth in the appended claims, reference being had to the accompanying drawings and to the characters of reference thereon which form a part of this specification, in which:—

Figure 1 is a side view of one form of my key complete, Fig. 2 is a side view of the part that remains in the door lock when the door is locked, Fig. 3 is an end view thereof showing by dotted lines the position of spring when the door is locked and the handle removed, Fig. 4 is a side elevational view of the part that remains in the door when locked shown in a slightly modified form, Fig. 5 is a fragmentary side view of the handle portion adapted to fit the shank of the door lock portion shown in Fig. 4, Fig. 6 is an end view thereof, and Figs. 7, 8 and 9 show the same as Figs. 4, 5 and 6 in a slightly modified form.

Similar characters of reference refer to similar parts throughout the several views.

The handle piece 1, lock piece 2 and

spring piece 3, constitute the principal parts of my key construction.

The lock piece 2 is a pin provided with a flat blade or lug 2^a on one side. This lug 2^a may be of various shapes and sizes with parts cut away to fit a variety of locks as the ordinary key is made. It is provided with a collar 2^b around the main portion and extending therefrom for some distance is a square spindle 2^c, upon the end of which is another collar 2^d. Extending from this collar 2^d is a round spindle 2^e with flattened sides or there may be a variety of shaped spindles, a few of which are shown in the different forms shown in the Figs. 2 to 9 inclusive. Upon the square spindle 2^c is mounted the spring 3 which is shaped as shown best in Figs. 2 and 3. It is double with the extended ends coming close together at point 3^a and is provided with a lug 3^b which extends close to the connection piece 2^e. This spring is adapted to fit tightly around the square piece 2^c so that when turned relatively to said piece it will form a spring lock for each quarter revolution of the piece 2. The handle piece 1 is preferably provided with a loop 1^a on its one end similar to the ordinary key and on its other end is provided with a variety of shaped caps adapted to fit the connection pieces 2^e of the pieces 2, the shapes being various the same as the shapes of the connection pieces 2^e so that a large variety of shapes and forms may be used. This extending end 1^b is flat on two sides in each case and provided with a flange the rest of the way around adapted to engage with the lug 3^b on the spring 3 when in a certain relative position to the piece 3, but when turned a quarter of the way around the flat surface is adjacent to said lug 3^b and the handle piece may be removed, leaving the pieces 2 and 3 in the keyhole of the lock.

It will be here noted that the blades 2^a show a simple blade for turning the tumblers of an ordinary lock, but it may be of any shape desired and of various shapes to turn a variety of locks; that the connecting pieces 2^e and the conforming portion 1^b of the handle piece may be of various shapes for tortional connection, so long as they allow the removal of the handle piece when the blade 2^a and the spring piece 3 are at right angles to each other; otherwise the handle piece 1 and piece 2 are held together

by means of the flange on portion 1^b and the lug 3^b on the spring 3.

Though I have shown and described a particular construction and arrangement of parts and several forms of connecting the handle piece with the lock piece, I do not wish to be limited to this particular construction and to these particular forms, but desire to include in the purview of my invention the construction, combination and arrangement substantially as set forth in the appended claims.

It is obvious that with this construction there is provided a key made in two general parts, one of which remains in the door lock when locked and the other portion is removed and may be carried by the user of the key; that it may be used on either side of the door as desired; that the spring piece 3 will remain downward at all times fitting the keyhole, and the handle piece can only be removed when the blade 2^a is turned at right angles thereto or in a horizontal plane and that in unlocking the door the handle piece must be put in the same position to remove the part 2, which is done by simply pushing in and turning it one quarter of the way around or until the key blade is down, when the lug 3^b engages with the flange on the portion 1^b and the key is removed, including the lock piece; that the spring piece 3 mounted tightly on the square portion forms a spring lock with each quarter revolution of the piece 2 relatively to said spring piece.

Having thus described my invention, what I claim as new and desire to secure by Letters Patent, is:

1. In a separable key the combination of a key divided into two parts, and a spring means mounted on one of said parts adapted to engage and disengage said parts when in certain relative position on said part.

2. In a separable key the combination of a handle part, a lock part, a spring mounted on said lock part engaging with said handle

part adapted to allow the handle to be removed when the handle part is in certain relative position to the spring part.

3. In a separable key the combination of a pin provided with a lug thereon adapted for turning the lock, said pin portion provided with a square portion, a spring mounted on said square portion and a handle portion engaging with said pin portion provided with oppositely disposed lugs adapted to engage with said spring portion when turned in certain position to said spring portion, but to be readily disengaged when in other relative positions.

4. In a separable key the combination of a pin provided with a lug thereon adapted for turning a door lock, said pin provided with a square portion, an extended spring provided with a lug mounted on said square portion and a handle part engaging with said pin provided with oppositely disposed lugs adapted to engage with said lug on said spring when turned in certain position to said spring, but to be readily disengaged when in other relative positions.

5. In a separable key the combination of a pin provided with a lug or blade thereon of the conventional kind adapted for turning an ordinary lock, said pin provided with a square portion, a spring mounted on said square portion adapted to lock each quarter turn of said square portion, and a handle part engaging with said pin provided with oppositely disposed lugs adapted to engage with said spring portion when turned in certain position to said spring portion, but to be readily disengaged when in other relative positions.

In testimony whereof, I have hereunto subscribed my name in the presence of two subscribing witnesses.

MYRON W. WIARD.
